COMBINED GARDEN RAKE AND HOE

William J. Roberts, Portland, Oreg., assignor to Jeanie
Rake-Hoe Co., Inc., a corporation of Oregon

Filed Apr. 11, 1967, Ser. No. 6,629

Term of patent 14 years

(CL. D39—1)

FIG. 1 is a front elevational view of a combined garden rake and hoe showing my new design;

FIG. 2 is a top plan view thereof; and

FIG. 3 is a side elevational view thereof.

I claim:

The ornamental design for a combined garden rake and hoe, as shown.
